E. B. ASHMORE.
 CURTAIN POLE CONCEALING SUSPENSION MEANS FOR DOUBLE FABRIC DRAPERIES.
 APPLICATION FILED MAY 19, 1914.
1,109,608.

Patented Sept. 1, 1914.

UNITED STATES PATENT OFFICE.

EDITH BANCROFT ASHMORE, OF PHILADELPHIA, PENNSYLVANIA.

CURTAIN-POLE-CONCEALING SUSPENSION MEANS FOR DOUBLE-FABRIC DRAPERIES.

1,109,608.

Specification of Letters Patent.

Patented Sept. 1, 1914.

Application filed May 19, 1914. Serial No. 839,540.

To all whom it may concern:

Be it known that I, EDITH BANCROFT ASHMORE, a citizen of the United States of America, and a resident of Philadelphia, in the county of Philadelphia and State of Pennsylvania, have invented certain new and useful Improvements in Curtain-Pole-Concealing Suspension Means for Double-Fabric Draperies, whereof the following is a specification.

The object of this invention is to provide a suspension means for curtains, portières and similar draperies which may be readily applied to the curtain without stitching and which will suspend it in such a manner as to cover and conceal the pole from view on both sides of the curtain or portière.

The invention is especially adapted for double portières or portières composed of two thicknesses of the same or different fabrics.

Figure 1 of the accompanying drawings represents an elevation of one side of a fragment of a double fabric portière suspended from a curtain pole by one embodiment of this invention, a central portion of one constituent fabric being broken out to better show said embodiment. Fig. 2 represents a vertical section thereof on line 2—2 of Fig. 1 extended to show the ends of the fabrics united at one end of the curtain. Fig. 3 represents a top plan view thereof. Fig. 4 represents a top plan view of another form of pole spanning carriage in which the arch consists of a single strand composed of two wires twisted together and provided with anti-friction rollers.

The same reference numbers indicate corresponding parts in the different figures.

This drapery suspension pin comprises a traveling carriage or slide freely movable along the curtain pole and upturned pins at opposite sides thereof adapted to penetrate both layers of the double fabric curtain or double portière and hold them up on opposite sides of the pole so as to conceal both faces thereof.

The drawings show two embodiments of the invention.

In the preferred form of embodiment shown in Figs. 1 to 3, the device is composed of two strands *a* and *b* of brass, steel or other wire. The traveling carriage or slide 10 constitutes the center of the structure. This carriage is preferably arc-shaped to fit over the top of a round curtain pole 50, but

it may be of other shape to fit a pole of other form in cross section. The carriage has preferably a divided span composed of parts of both strands *a* and *b* disposed apart from each other. The carriage has shanks 20 and 25 connected with the opposite ends of the top span and dependent from opposite sides of the carriage. Each shank is preferably composed of portions of the wires *a* and *b* twisted together. The upper end of the shank 20 is connected with the divided span of the saddle or slide 10 at one end thereof by angular bends 11 and 12 and the shank 25 is connected with said spans at the other ends thereof by angular bends 13 and 14. These bends may be at forty-five degrees or any other suitable angle. The wires *a* and *b* diverge in opposite directions from the lower end of the shank 20, preferably horizontally at right angles to said shank and substantially longitudinally with reference to the pole and form spreading bars 21 and 22. Similar spreading bars 26 and 27 are formed at the lower end of the shank 25. The wires *a* and *b* are bent upward at the outer ends of the spreading bars aforesaid and form upturned vertical pins 30 and 35 on one side of the carriage 10 and upturned vertical pins 40 and 45 on the other side thereof. These pins are sharp pointed at their upper ends and are elongated to hold the fabrics at the top or heading of the curtain sufficiently high to cover the pole 50 and curtain fixtures so that they cannot be seen from either side of the curtain or sufficiently high to also close the space between the pole and the top of the opening or doorway as indicated in Figs. 1 and 2. The carriage or slide 10 is preferably provided with anti-friction rollers 15 to facilitate its movement along the curtain pole.

In Fig. 4 the carriage is composed of a single central span 110, the wires *a* and *b* being twisted together across the top of the device instead of being separated as in the other embodiment herein illustrated. This single span carriage may also be provided with antifriction rollers 15.

This drapery suspension means is especially useful in connection with a curtain or portière composed of two fabrics 60 and 65, which may be united along their vertical ends by seams as 66. These seams do not extend to the top of the curtain and the heading portions of the fabrics are

separable to permit the entrance of the pole between them, as clearly shown in Fig. 2.

In applying this duplex suspension pin, the pins 30 and 35 on one side of the slide 10 are inserted in the heading of one fabric as 60 of the double curtain and the pins 40 and 45 on the other side of the slide 10 are inserted in the heading of the other fabric as 65 of said curtain. A sufficient number 10 of suspension pins are so applied to the curtain and then the curtain pole 50 is passed between said fabrics at the upper end of the curtain and under the carriages 10, and then the pole is placed in position on its 15 supports.

This duplex suspension pin is especially applicable to curtains or portières which are plaited and the pins 30 and 35 on one side of the carriage 10 are made to engage adjacent plaits of one fabric of the double curtain and the pins 40 and 45 are made to engage adjacent plaits of the other fabric thereof. The spreading bars 21, 22, 26 and 27 extend across the joints between the folds 25 and hold them in place.

The form of embodiment may be varied as regards specific details thereof without a departure from the invention claimed.

I claim as my invention:

- 30 1. A duplex drapery suspension pin composed of wire strands forming a central carriage having an arched span adapted to slide on a curtain pole, shanks integral with said span and extending downward from opposite ends thereof, spreading bars disposed at right angles to the span of the carriage and integral with said shanks, and upturned pins at the outer ends of said spreading bars.
- 35 2. A duplex drapery suspension pin composed of wire strands forming a central carriage provided with anti-friction rollers and having dependent twisted shanks on its op-

posite sides, spreading bars at the lower ends of said shanks, and upturned pins at 45 the outer ends of said spreading bars.

3. A duplex drapery suspension pin composed of wire strands forming a central carriage having a divided top span and dependent twisted shanks at its opposite sides, spreading bars at the lower ends of said shanks, and upturned pins at the outer ends of said spreading bars.

4. A duplex drapery suspension pin composed of wire strands forming a central 55 carriage having dependent twisted shanks at its opposite sides, spreading bars at the lower ends of said shanks, and upturned pins at the outer ends of said spreading bars, said pins being operative to hold the 60 fabrics of a double curtain in concealing position on opposite sides of a pole.

5. A duplex drapery suspension pin composed of wire and comprising a central straddling carriage adapted to travel on a 65 curtain pole, and upturned pins integral with said carriage on opposite sides thereof, 70 said pins being adapted respectively to engage separate fabrics of a double curtain or curtains.

6. A duplex drapery suspension pin composed of wire and comprising a central straddling carriage adapted to travel on a curtain pole, and upturned pins integral with said carriage on opposite sides thereof, 75 said pins being adapted respectively to engage separate fabrics of a double curtain or curtains and being elongated to extend upward on opposite sides of said pole to hold said fabrics in position to conceal the pole 80 on both sides thereof.

EDITH BANCROFT ASHMORE.
